UNITED STATES PATENT OFFICE.

ELWOOD B. AYRES AND ALPHEUS O. HURXTHAL, OF PHILADELPHIA, PENNSYLVANIA,
ASSIGNORS TO PROCTOR & SCHWARTZ, INC., OF PHILADELPHIA, PENNSYLVANIA, A
CORPORATION OF PENNSYLVANIA.

DRIER.

Application filed May 26, 1923. Serial No. 641,582.

To all whom it may concern:

Be it known that we, ELWOOD B. AYRES and ALPHEUS O. HURXTHAL, citizens of the United States, residing in Philadelphia, Pennsylvania, have invented certain Improvements in Driers, of which the following is a specification.

The object of our invention is to improve the means for circulating air in drying apparatus so that the air in circulation will be distributed evenly in the drying chamber, the material located in said chamber being uniformly dried.

In the accompanying drawings:

Fig. 1 is a sectional elevation illustrating our improvements in drying apparatus;

Fig. 2 is a sectional plan view; and

Fig. 3 is an enlarged detail of the air baffle.

Referring to the drawings, 1 is the casing of the drier. 2 is a vertical partition, which separates the drying chamber 3 from the heating chamber 4. 5 designates a horizontal, foraminous partition, which forms a baffle having a series of cross slats providing ducts through which the air passes to the drying chamber. Above the partition 5 is a screen 6 of fine wire mesh, which tends to hold the air in check so that it will be distributed evenly over the entire surface of the screen. Above the screen is an air chamber 7, which is in communication through openings 8 with the upper end of the heating chamber 4.

In each opening 8 is a circulating fan 9, mounted on a driven shaft 10.

The lower end of the partition 2 stops short of the bottom of the drier so that air is free to circulate, as shown by the arrows. Any suitable heating device may be located in the chamber 4, or in the chamber 7. In the present instance, steam coils 11 are shown in the heating chamber.

12 designates trucks located in the drying chamber. These trucks are so designed as to support properly the material to be dried. At each end of the drier are doors 13 so that the trucks can enter one end of the drier. When the material is in proper condition, the trucks can leave the drier 50 through the opposite doorway.

The drier may be of any length desired, depending upon the material to be dried and the capacity of the factory in which the drier is installed.

The operation is as follows: When the 55 trucks are located in the drying chamber and the doors are closed, the fans are set in motion and the heated air is forced in the chamber 7 above the horizontal partition 5. The meshes of the screen are such that 60 the air in the chamber will be under pressure and will be forced through all of the meshes of the screen at about the same pressure and will be directed downwards by the cross slats of the partition 5, insuring even 65 drying of the material on the trucks. The air, in passing from the drying chamber, travels under the partition 2 into the heating chamber, where it is reheated. Suitable openings for fresh air and suitable vents 70 for moist air may be provided, if desired.

We claim:

1. The combination in a drier, of a drying chamber; an air chamber above the drying chamber; a fine wire screen and a foraminous partition arranged in close proximity one with the other and separating the two chambers; and means for circulating heated air, the air being forced into the air chamber where it accumulates and passes 75 through the meshes of the wire screen and the foraminous partition and into the drying chamber.

2. The combination in a drier, of a casing; a vertical partition separating a drying chamber from a heating chamber; a horizontal, foraminous partition separating the drying chamber from an air chamber; a fine mesh screen located above the partition; and means for circulating air in the drier. 85

3. The combination in a drier, of a casing; a vertical partition separating a drying chamber from a heating chamber; a horizontal, foraminous partition separating the drying chamber from an air chamber, said 90 partition being formed by cross slats spaced apart; a fine mesh screen located directly above said partition, the vertical partition having a fan opening forming a communication between the heating chamber and 100 the air chamber; a circulating fan in said opening; and trucks in the drying chamber, said chamber having doors for closing the ends thereof.

ELWOOD B. AYRES.
ALPHEUS O. HURXTHAL.
